UNITED STATES PATENT OFFICE.

HORATIO L. HALL, OF CHICAGO, ILLINOIS, ASSIGNOR TO THE AMERICAN SCHOOL FURNITURE COMPANY OF SAME PLACE AND NEW YORK, N. Y.

DESIGN FOR A STANDARD FOR SCHOOL-DESKS.

SPECIFICATION forming part of Design No. 31,287, dated July 25, 1899.

Application filed June 14, 1899. Serial No. 720,567. Term of patent 3½ years.

To all whom it may concern:

Be it known that I, HORATIO L. HALL, a citizen of the United States, residing at Chicago, in the county of Cook and State of Illinois, 5 have invented and produced a new and original Design for a Standard for School-Desks, of which the following is a specification, reference being had to the accompanying drawing, which forms a part hereof.

10 As shown in the drawing, my design consists of a standard for a school-desk having the legs *a* and *b* of convex section, the curved edges *c* for the seat, and the curved edge *d* for the back, the straight edge *e* of the top of 15 the desk making an angle with the back edge *d*, as shown, the whole presenting a neat and

ornamental appearance. Across the standard near the top is an opening *f*, in which any desired distinguishing-name may be placed.

The leading or material feature of my design consists of a standard for a school-desk, substantially as shown and described.

Having thus described my invention, what I claim as new, and desire to secure by Letters Patent, is—

25 The design for a standard for a school-desk as herein shown and described.

HORATIO L. HALL.
